UNITED STATES PATENT OFFICE.

CARL G. ULLIN, OF SEATTLE, WASHINGTON.

SUBMARINE LIFE-SAVING APPLIANCE.

1,128,553.

Specification of Letters Patent. Patented Feb. 16, 1915.

Application filed January 8, 1914 Serial No. 810,963.

To all whom it may concern:

Be it known that I, CARL G. ULLIN, a citizen of the United States, residing at Seattle, in the county of King and State of Washington, have invented certain new and useful Improvements in Submarine Life-Saving Appliances, of which the following is a specification.

This invention relates to submarine vessels and more especially to apparatus whereby the crews thereof may escape in emergencies such as the disability of a vessel.

The object of the invention is the provision of a buoyant water-tight structure into which the crew enter and upon its being released from a sunken vessel will carry them in safety to the water surface.

The invention consists in the novel construction and adaptation of devices, as will be hereinafter described and claimed.

In the accompanying drawings, Figure 1 is a vertical longitudinal section of a portion of a submarine vessel with the present invention applied thereto. Figs. 2 and 3 are horizontal sections through 2-2 and 3-3 of Fig. 1. Fig. 4 is a detail sectional view taken through 4-4 of Fig. 1 to illustrate the valve for controlling the admission of water to flood the compartment containing the buoyant caisson. Fig. 5 is a perspective view of the upper end of the valve controller rod.

The reference numeral 10 designates the deck and 11 the bottom plating of the shell of a submarine vessel. Provided within said vessel is a watertight compartment 12 which is desirably of a substantially cylindrical form and extends from the bottom plating 11 to the deck 10. The peripheral wall or bulkhead 13 which incloses said compartment is provided near its upper end with a way 14 of sufficient size for the passage of people therethrough and is normally closed by a door 15. Steps 16 may be provided on the exterior of the wall 13 below the doorway. A hatch-cover 17 is provided on the deck 10 for closing the opening at the top of the compartment 12. Said hatch-cover is hinged at one edge, as at 18, and adjacent its other edge the cover is provided with a depending bolt 19 which terminates in a horizontal finger 20. A

water inlet valve 21 is provided to close an opening 22 provided in the bottom plating 55 11 and similarly a vent-valve 23 is provided for closing an opening 10¹ in the deck 10. These valves are advantageously of the type known as swinging gate-valves and operate between seats 21¹ and 23¹ for the respective 60 valves. Said valves are rigidly connected or secured as by welding upon an upright rod 24, which is socketed at its ends for rotary movements.

Coextensive with the valve 23 is an arm 65 25 which serves as a latch member with respect to the hatch-cover 17 by engaging the finger 20 of the aforesaid bolt. Said valves and the arm 25 are arranged so that when the rod 24 is suitably turned the valves will 70 be closed while the cover is latched; and likewise when the rod is turned to open the valves the cover is unlatched. In order to make the compartment of small diameter, an offset chamber 26 is provided for the 75 valve rod and communicates at the top and bottom with the compartment 12. Located within said compartment is a tubular structure which, for convenience, will be herein-after designated as the caisson. This caisson is formed with a peripheral wall 27, a bottom wall 28 and a partition 29 at a distance above the latter. At the top, the caisson is provided with a lid 30 which is openable upward about hinge 31 and is secured 80 in closed position by a fastening screw-bolt 32 and a winged nut 33. The lid is formed with a dome-like central portion to accommodate the head of a person when looking out of glazed sight apertures 34 provided 90 in the dome. Near the upper end of the caisson and facing the wall-opening 14 of compartment 12, is a way 35 for which is provided a door 35¹.

36 represent spaced shelves upon which 95 people may stand or sit when the caisson is employed.

37 is a valve for controlling an opening 38 in the caisson wall and communicating with the water ballast chamber 39 which is 100 afforded between the partition 29 and bottom wall 28. The valve 37 is operated by a screw stem 40 engaging in a fixed nut 41, so that when the stem is turned through the medium of a wheel 42, the valve is opened or 105 closed.

43 represents a pump having its suction pipe 44 extending into the ballast chamber 39 and its discharge pipe 45 disposed to deliver the water through an opening (not shown) provided in the caisson wall 27. The pump-handle 46 is operable by a man within the caisson.

The caisson is supported upon a platform 47 and secured thereto is a receiver 48 for a latch-finger 49 of an upright shaft 50 which extends upwardly into the interior of the caisson. 51 is an arm extending from shaft 50 and engaging between the branches of a bifurcated arm 52 (Fig. 3) provided on the rod 24. A crank handle 52 is provided for turning shaft 50.

In operation, the crew of the vessel enter the caisson through the doorways 14 and 35 whereupon the respective doors 15 and 35 are closed and fastened. One of the occupants then opens the valve 37 and also turns the shaft 50 resulting in the swinging of the latch-finger 49 from the receiver 48 and also of the turning of the rod 24 through the instrumentality of the arms 51 and 52 on the shaft and rod, respectively. When the rod is thus turned, the latch-finger 25 is withdrawn from engagement with the bolt 19 thereby unfastening the cover 17. 30 The rod furthermore effects the opening of the valves 21 and 23 so that water can enter the compartment 12. As the water ascends it will flow into ballast chamber 39 and eventually fill the compartment about the 35 caisson. When this occurs, the water pressures acting from above and below upon the cover 17 will balance, but in consequence of the buoyancy of the caisson, the latter will cause the cover to rise. When 40 the cover opens, the caisson will rise to the water surface. Should the caisson be too heavily loaded to have the upper end of the caisson protrude the desired height above the water surface, the pump 43 may be uti-

lized to discharge water from chamber 39 45 subsequent to the closing of valve 37.

The exterior surface of the caisson, at least at the top and including the lid 30, is covered with a substance such as a coat of mercury with a layer of varnish or an equivalent transparent material thereover. By such devices the caisson will be invisible to an observer inasmuch as he will see only the reflection of the surrounding water surface.

The various doors and the caisson lid would, of course, be fitted to make watertight joints with the body of the caisson, or be rendered so by the use of a suitable packing or gaskets.

The releasing means for the caisson, the lid thereof and the cover of the containing compartment 12, are all operated by the crank-handle 52 which also opens the valves 21 and 23 which allow of the flooding of 65 said compartment. Under such conditions there would be no liability of any mistake being made as would be the case with a number of separate controllers for the individual above-named elements.

What I claim as my invention, is—

The combination with a submarine vessel provided with a compartment therein which is open at the top, a cover for the compartment opening, fastening means for said 75 cover, and valves for the admission of water into said compartment, of a buoyant structure within said compartment, of means operable from within the structure whereby said valves may be opened and the fastening means for the compartment cover rendered inoperative.

Signed at Seattle, Wash., this 30th day of December, 1913.

CARL G. ULLIN.
